SUBMARINE DEPTH TORPEDO

Rafael Gimenez Ruiz, Canlubang, Laguna, P. I.,
Vested in the Alien Property Custodian

Application September 23, 1938, Serial No. 231,430

1 Claim. (Cl. 102—10)

My invention relates to explosives and includes among its objects and advantages the provision of an improved submarine depth torpedo.

An object of my invention is to provide a torpedo which may be released underneath an enemy ship or the like in which the torpedo is so constructed as to arise vertically from a considerable distance beneath the ship and in which means are incorporated for exploding the torpedo as it contacts with the ship.

In the accompanying drawings:

Figure 1 is an elevational view of a torpedo embodying my invention;

Figure 2 is a similar view of a differently shaped torpedo;

Figure 3 is a sectional view along the line 3—3 of Figure 1;

Figure 4 is an enlarged sectional detail view of the fuse cap mounts and the hammers therefor;

Figure 5 is a view similar to Figure 4 but illustrating the structure from a different angle;

Figure 6 is a sectional view of one of the fuse caps;

Figure 7 is a sectional view along the line 7—7 of Figure 6;

Figure 8 is an end view of the fuse caps;

Figure 9 is an enlarged sectional detail view along the line 9—9 of Figure 3;

Figure 10 is an end view of the structure of Figure 9;

Figure 11 is a sectional view along the line 11—11 of Figure 9; and

Figure 12 is a view of a wrench employed in assembling some of the parts of Figure 9.

In the embodiment selected to illustrate my invention, the torpedo 10 comprises a nose section 12 containing explosive 14 and a section 16 which may be filled with hydrogen gas for lending buoyancy to the torpedo. Sections 12 and 16 include threaded flanges 18 for threaded connection with a connecting ring 20 having a wall 22 which constitutes a partition. Thus the sections 12 and 16 are detachably connected, while the wall 22 separates the explosive containing chamber from the gas chamber. Wall 22 includes threaded openings 24 for the reception of threaded closure plugs 26. Openings 24 may be employed for loading the nose 12 with explosives.

Wall 22 includes a flange 28 internally threaded for the reception of a nipple 30 internally threaded for connection with a neck 32 associated with the fuse cap support 34. Figures 4 and 5 illustrate the specific construction of the fuse

cap support 34. To the flat wall 36 I secure plates 38 by means of rivets 40, while the plates 38 include flanges 42 which project through openings 44 in the wall 36. The fuse caps 46 are positioned inside the flanges 42 and are held in place by means of clips 48 which may be movably connected with the plates 38 by screws 50. Clips 48 may be pivoted in the clear of the flanges 52 of the fuse caps, and when positioned according to Figure 5, the fuse caps will be restrained from longitudinal shifting relative to the flanges 42.

Fuse cap support 34 includes a neck 54 having threaded connection with a tube 56 threaded into the flange 58 located at the apex of the nose 12. Nose 12 includes a bore 60 for slidably receiving a trigger rod 62. The nose 12 includes a larger bore 64 within which I provide packing 66. Rod 62 includes a contact head 68 arranged to engage the vessel or other object to be blown up for releasing the hammers which are operatively related to the fuse caps 46. Tube 56 includes a guide 70 for the trigger rod 62. Upon the trigger rod 62 I mount a compression spring 72 which abuts the guide 70 and a flange 74 fixed to the rod. Spring 72 normally urges the flange 74 against the face 76, but the rod may be moved inwardly through contact with a vessel or other object.

Upon the flanges 18 of the plates 38 I mount rods 80 upon which hammers 82 are pivotally mounted. Figure 5 illustrates coil springs 84 as being mounted upon one of the rods 80 and shaped to have ends 86 bearing against the plates 38 and ends 88 bearing against the hammers 82. Figure 4 illustrates the normal position of the hammers 82. A flange 90 is fixedly connected with the inner end of the trigger rod 62 and is arranged to have latching relation with the ledges 92 formed on the hammers 82. Springs 84 are under increased tension with the hammers 82 positioned in their full line illustrations of Figure 4. Inward movement of the rod 62 pushes the flange 90 out of holding relation with the hammers for releasing the latter. Each hammer includes a bulge 94 arranged to contact its respective fuse cap 46, as at 96 for firing the same. Springs 84 are of such tension as to drive the hammers 82 with sufficient force to fire the fuse caps. The cartridge part 98 of the fuse caps 46 extend into the explosive 14, as illustrated in Figure 3.

Section 16 includes a threaded bore 100 for connection with the exteriorly threaded tube 102. I provide the section 16 with flat faces 104 against

which I place washers 106 and fixedly secure the tube 102 by means of nuts 108. Tube 102 includes a thick end 110 having a threaded bore 112 for threaded connection with a small tube 114 normally closed at its outer end by a detachable cap 116. A sealing washer 118 embraces the tube 114 and bears against the flat face 120 of the end 110. The sealing washer 118 is compressed through the medium of a nut 122 having threaded relation with the tube 114. A valve 124 is arranged to have seating relation with the inner end of the tube 114 and is connected with rods 126 and 128. Rod 128 is slidably guided by spiders 130 anchored inside the tube 114, while rod 126 is slidably guided by a spider 132 threaded to the tube 102 as at 134. Valve 124 is urged into seating relation with the tube 114 by means of a compression spring 136 abutting the valve and the spider 132.

To facilitate assembly of the tube 114 with the end 110, I provide the tube with a flange 138 having a square opening 140 for receiving the square head 142 of the tool 144. Hydrogen gas or other equivalent material for lending buoyancy to the torpedo is introduced into the section 16 through the tube 114. Cap 116 may be removed to permit connection between the tube 114 and a suitable conduit for the introduction of the gas. Gas under pressure will of course raise the valve 124 to permit passage of gas into the section 16. Spring 136 holds the valve in a closed position in the absence of filling pressure inside the tube 114. Rod 128 terminates in close relation with the outer end of the tube 114 and may be positively lifted through the medium of suitable coupling means while the gas is being introduced into the section 16. Such devices are well-known in the art and need not be described in further detail.

I provide the cap 116 with a gasket 146 which abuts the end of the tube 114 for sealing purposes. To the section 16 I connect a plurality of stabilizers 148 which guide the torpedo in a straight, vertical path after being released. The buoyancy of the torpedo is such as to carry it upwardly into contact with the object to be de-

molished. The torpedo may be released from a submarine passing underneath the object to be demolished. The submarine would release the torpedo at such a depth as to permit the submarine to move a considerable distance from the point of release during the travel of the torpedo in the direction of its target.

Figure 2 illustrates a torpedo 150 having the configuration of a cigar. In all other respects the torpedo 150 is identical with the torpedo 10 and operates in the same manner.

As clearly shown in Figures 1, 2 and 3 the lower section 16 of the torpedo is greater in axial dimension than the upper section 12, and the vanes or stabilizers 148 are carried solely by the lower section and increase in width in the direction of the lower end of the torpedo. The greater axial dimension of the lower section 16, and the location of the vanes or stabilizers 148 on this section, places the center of gravity of the torpedo sufficiently low to insure its rising in the water with the firing pin at the top.

I claim:

A torpedo of the character described, comprising a shell consisting of upper and lower sections, a transverse partition between the sections separating the shell into an explosion chamber and a buoyancy chamber, the shell being provided at its periphery with a flange with which the sections are screw threadedly engaged to secure the sections in assembled relation, an explosive material in the explosion chamber, a tube located axially in the explosion chamber and secured to the partition and to the shell, percussion caps carried by the tube and extending therefrom into the explosive material, pre-tensioned hammers for the percussion caps pivoted to and within the tube, a rod slidably mounted in the tube and provided at its inner end with a flange engaging the hammers to hold them in retracted position, the rod extending through and beyond the explosion chamber to provide a target engaging element, and a spring normally holding the rod against movement.

RAFAEL GIMENEZ RUIZ.
